UNITED STATES PATENT OFFICE.

THOMAS ANDREW LEE MOORE, OF RICHMOND, VIRGINIA, ASSIGNOR OF FIVE-EIGHTHS TO SAMUEL T. ATKINSON AND DRURY SAMUEL HARDY, OF SAME PLACE.

TRACK-GROOVE CLEANER.

SPECIFICATION forming part of Letters Patent No. 614,122, dated November 15, 1898.

Application filed March 8, 1898. Serial No. 678,065. (No model.)

To all whom it may concern:

Be it known that I, THOMAS ANDREW LEE MOORE, a citizen of the United States, residing at Richmond, in the county of Henrico and State of Virginia, have invented certain new and useful Improvements in Track-Groove Cleaners; and I do hereby declare the following to be a full, clear, and exact description of the invention, such as will enable others skilled in the art to which it appertains to make and use the same.

My invention relates to an apparatus for cleaning the grooves of street-car-track rails.

The object of the invention is to provide a simple and effective apparatus of this character designed to clean the rail-grooves in the most effective manner and which is adapted to be thrown into or out of operation at will by the motorman from his position on the car-platform.

To this end the invention consists in the features and in the construction, combination, and arrangement of parts hereinafter more fully described, and specifically set forth in the appended claims, reference being had to the accompanying drawings, in which—

Figure 1 is a part sectional and part side elevational view of one end of a car having my invention applied thereto. Fig. 2 is a top plan view of the rock-shaft and cleaning-plows carried thereby. Fig. 3 is a broken detail view, in front elevation, of one of the plows. Fig. 4 is an inner perspective view of same, looking toward the front end thereof. Fig. 5 is an outer perspective view of the plow, looking toward the rear end thereof.

Referring now more particularly to the drawings, A represents a portion of the body of an electric or other motor car, B the platform at the end thereof, and C the usual dash rising from said platform. On the dash is a fixed bearing d, which in practice is preferably arranged between the controller-box and brake-handle when the apparatus is used on an electric car, and mounted to slide vertically in this bearing is a tubular operating-shaft E, provided with an intermediate series of rack-teeth e and with a handle f at its upper end. Pivoted to the bearing is a suitable latch device adapted to engage the teeth and

hold the shaft elevated, said latch device consisting in the present instance of a pawl g, having a handle g', whereby it may be conveniently disengaged from said teeth whenever it is desired to allow the shaft to drop 55 down by gravity. The lower end of the shaft is closed by a screw-cap h, to which is rigidly connected the upper end of a rod H, which extends downwardly through an opening in the platform and through a guide-plate i on 60 the bottom of the platform, and a cushion block or disk j, of rubber or leather, on the top thereof, said block or disk being held in position by means of a plate j' and serving to cushion and deaden the force of impact of 65 the shaft E when the latter is allowed to fall.

The lower end of the rod H is provided with a head k and is fitted to slide within a vertical cylinder K, and this cylinder is closed at its upper end by a screw-cap l, having an orifice 70 to receive said rod. Threaded into the lower end of the cylinder is a sleeve m, which receives the upper screw-threaded end of a bifurcated bracket n, to which the forward end of an operating-lever O is pivoted, as shown 75 in Fig. 1. Inclosed in said cylinder is a spiral spring l', which encompasses the rod between its head k and the screw-cap l. The function of this spring is to retain the parts in their relative positions and also to allow freedom of movement of said parts to compensate for the vertical oscillatory motion of the car body and platform.

The rear end of the operating-lever O is rigidly connected to a transverse rock-shaft P, 85 mounted in hangers or bearing-brackets p, fixed to the transverse fender-bar P, arranged adjacent to the wheels Q. These hangers or brackets are provided with cups or in lieu thereof with oil-holes for the purpose of enabling the rock-shaft to be readily and conveniently lubricated. By this construction it will be seen that while the rock-shaft is mounted to oscillate in the hangers the latter are adapted to slide freely longitudinally on 90 said shaft, so as to permit lateral or sidewise motion of the car without affecting the rock-shaft or the cleaning mechanism carried thereby. Rigidly mounted on each end of the shaft is a sleeve R, which may be secured 95 100

thereto in any desired manner, and each of these sleeves carries an inwardly-projecting arm S, having an upwardly-bent inner end s. To these ends of the arms are secured the 5 track-groove-cleaning devices T, which are for convenience of description herein termed "plows."

Encompassing the rock-shaft between the hangers n and sleeve R are spiral springs t. 10 The function of these springs is to hold the shaft and plow in proper working position at all times, thereby obviating any tendency of the shaft to move laterally or sidewise as the hangers slide thereon. Each plow T is formed 15 of a sheet-steel plate and is constructed with a body portion or outer side portion u, bent inwardly and upwardly at its lower end to form a shorter parallel inner side plate or flange v and a rounded or approximately 20 scoop-shaped bottom w. The front end of each plow is beveled off at its lower portion to form a cutting edge x, while its rear end x' is curved or deflected inwardly, so as to throw the dirt and caked grease removed from the 25 track-grooves by the plow in the track-bed between the two rails, so as to obviate any liability of the dirt falling back again into the grooves. In order to effectually attain this result, I provide the plow with an inwardly-projecting guide or deflector plate y, 30 bolted to the rear end thereof, which plate conducts the dirt falling out at the rear end of the plow to the inner side of the track-rail, as will be readily understood. The outer side 35 plate or body portion u of the plow is bolted or otherwise suitably secured to the upwardly-projecting end s of the arm S, as clearly shown in Figs. 1 and 5.

The operation is as follows: When it is desired to clean the rail-grooves, the operating-shaft E is drawn upward by means of its handle f, thereby drawing upward on the forward end of the operating-lever O and tilting the rock-shaft, which causes the arms S to move downwardly and bring the cutting edges of the plows into the grooves z of the track-rails Z, as clearly shown in Fig. 1. By reference also to this figure it will be seen that the plows when in operative position are inclined 45 at an angle of about twenty degrees and that they are arranged in close proximity to the wheels Q. From this construction it is apparent that as the car moves the cutting edges of the plows readily and cleanly remove the dirt retained within the grooves and that this dirt is forced back and discharged at the rear of the plow on the inner side of the rail. An important advantage residing 55 in the specific manner of constructing and arranging the plows herein described is that the beveled cutting edges cannot become dulled as they are constantly maintained and formed by wear. When it is desired to lift the plows out of the track-rail grooves, the 60 pawl g is released from engagement with the rack-teeth e and the shaft E allowed to drop down by gravity, whereupon the forward end

of the operating-lever O will be tilted downwardly and the arms S upwardly, thereby elevating the plows. The plows are arranged 70 in close relation to the wheels to permit of the sand-pipes being placed in front of said plows, so that when sand is thrown on the rails that portion thrown into the grooves may be removed by the plows without disturbing the sand on the faces of the rails. 75

From the above description, taken in connection with the accompanying drawings, it will be seen that my invention provides a simple and effective apparatus which may be 80 quickly and conveniently operated at will by the motorman standing at his proper position on the platform. It will also be seen that the construction and arrangement are such as to permit of the parts being thrown into and out 85 of action without exertion on the part of the motorman and that the duties of the motorman are not materially increased, inasmuch as it is only necessary to use the apparatus over the entire line once or twice a day. 90

I desire it understood that I do not limit my invention to the specific constructions and arrangement of parts herein shown and described, but reserve to myself the right to make such changes and modifications as fairly fall within the spirit and scope of my invention. 95

Having thus described my invention, what I claim as new, and desire to secure by Letters Patent, is—

1. In a rail-groove cleaner, the combination with a car, of a rock-shaft mounted in bearings on the under side of the car, rail-groove-cleaning plows carried thereby, a lever for operating said shaft to throw the plows into 105 and out of action, an operating device on the car-platform, and a yielding connection between said operating device and the free end of the lever, substantially as described.

2. In a rail-groove cleaner, the combination with a car, of a rock-shaft mounted in bearings on the under side of the car, rail-groove-cleaning plows carried thereby, an operating-lever connected with said shaft and adapted to normally tilt down and operate the shaft 115 to throw the plows out of action, an operating device on the car-platform for raising said lever, and a yielding connection between the free end of the lever and said operating device, substantially as described. 120

3. In a rail-groove cleaner, the combination of a rock-shaft mounted in bearings on the under side of the car, rail-groove-cleaning plows carried thereby, a lever connected with said shaft and adapted to tilt down to throw the plows out of action, an operating-shaft on the car-platform connected with said lever and adapted to drop by gravity, and a latch device adapted to engage said shaft to support it and the lever, substantially as described. 125

4. In a rail-groove cleaner, the combination of a rock-shaft mounted in bearings on the under side of the car, rail-groove-cleaning

5 plows carried thereby, a lever connected with said shaft and adapted to tilt down to throw the plows out of action, an operating-shaft on the car-platform, a yielding connection between the operating-shaft and free end of the lever, and a latch device adapted to engage said shaft to support it and the lever, substantially as described.

10 5. In a rail-groove cleaner, the combination with a car, of a rock-shaft mounted in the bearings on the underside thereof, rail-groove-cleaning plows carried thereby, a lever connected with the rock-shaft, a vertically-movable operating-shaft on the car, a cylinder 15 connected with the free end of the lever, a vertically-movable rod connected at its upper end with the operating-shaft and projecting through the platform and having its lower end inclosed in the cylinder, a tension-spring 20 in the cylinder acting on said rod, and a latch for holding the operating-shaft and free end of the lever elevated against the tension of said spring, substantially as described.

25 6. In a rail-groove cleaner, the combination with a car, of a rock-shaft mounted in bearings on the under side thereof, a pair of substantially scoop-shaped plows carried thereby provided at their front ends with cutting or scraping edges and at their rear ends with 30 lateral deflectors, said plows being arranged in close proximity to the wheels and inclined when in operation at an angle of about twenty degrees, an operating-lever connected with said shaft, an operating device on the car-platform, and a yielding connection between 35 said operating device and lever, substantially as described.

7. In a rail-groove cleaner, the combination with a car, of a rock-shaft mounted in bearings on the under side thereof, rearwardly-projecting arms carried by said shaft having upturned ends, a pair of substantially scoop-shaped plows connected with said upturned

45 ends of the arms and provided at their front ends with cutting or scraping edges and at their rear ends with lateral deflectors, said plows being arranged in close proximity to the wheels and inclined when in operation at an angle of about twenty degrees, and means for operating said shaft from the car-platform, substantially as described.

50 8. A rail-groove-cleaning plow comprising in its construction a comparatively long body portion having a curved or scoop-shaped bottom formed at its front end with a cutting edge and at its rear end with a deflector, substantially as described.

55 9. A rail-groove-cleaning plow comprising in its construction a body portion having a curved or scoop-shaped bottom provided with a cutting edge at its front end and an inturned rear end, and a deflector-plate at said rear end, substantially as described.

60 10. In a rail-groove cleaner, the combination with a car, of hangers pendent from the bottom thereof, a rock-shaft mounted to oscillate and to slide longitudinally in said hangers, arms projecting rearwardly from said shaft, rail-groove-cleaning plows carried by said arms, springs on the shaft between the hangers and arms to normally hold said arms and plows in operative position, an operating-lever connected with the rock-shaft and projecting forwardly therefrom, an operating-shaft on the car-platform, a yielding connection between the operating-shaft and front end of the lever, and a latch device to hold the operating-shaft and front end of the lever elevated, substantially as and for the purpose described.

70 80 In testimony whereof I affix my signature in presence of two witnesses.
